LEVER JAW CRUSHER

Charles J. Zillgitt, Pasadena, Calif.

Application December 11, 1933, Serial No. 701,829

3 Claims. (Cl. 83—53)

My invention relates generally to crushing machinery and more particularly to a crusher wherein a movable jaw is carried by the end of the short arm of a lever, which movable jaw is opposed by a relatively stationary jaw and the lever that carries the movable jaw being mounted so that when the lever is swung upon its fulcrum to move the jaw carried thereby toward the fixed jaw, said movable jaw has in addition to 5 said forward movement, a downward movement, that is highly effective in crushing the material that is delivered between the jaws.

This combined downward and forward movement of the movable crushing jaw is brought 15 about by the location of the fulcrum for the lever relative to the body of said lever and the jaw carried by the forward end thereof.

The principal objects of my invention are, to generally improve upon and simplify the construction of existing crushing machines, to provide relatively simple and effective means for actuating the lever that carries the movable jaw, to provide a crushing machine of the type referred to that may be very economically operated 25 in point of power requirements and further, to provide improved means for mounting the fixed and movable jaws in the frame of the machine.

Further objects of my invention are, to provide means for conveniently effecting the adjustment of the fixed jaw toward and away from the movable jaw and further, to provide a support for the fixed jaw which will automatically release said fixed jaw in the event that a metal object or a piece of uncrushable material enters the space 35 between the jaws, thereby eliminating the possibility of injury or breakage of the essential parts of the crushing machine.

With the foregoing and other objects in view my invention consists in certain novel features 40 of construction and arrangements of parts that will be hereinafter more fully described and claimed and illustrated in the accompanying drawings in which:

Fig. 1 is a top plan view of a crushing machine constructed in accordance with my invention.

Fig. 2 is a vertical longitudinal section taken on the line 2—2 of Fig. 1.

Fig. 3 is a horizontal section taken on the line 50 3—3 of Fig. 2.

Fig. 4 is a detail section taken on the line 4—4 of Fig. 3.

Fig. 5 is a detail section taken on the line 5—5 of Fig. 3.

Fig. 6 is a perspective view of one of the re-

movable plates that are arranged at the sides of the crushing cavity.

Referring by numerals to the accompanying drawings which illustrate a preferred embodiment of my invention, 10 designates a frame that is substantially rectangular in form and journaled in bearings 11 on one end of said frame is a shaft 12, provided on its intermediate portions with an eccentric 13.

Mounted on said shaft outside the frame, are 10 fly wheels 14 and one end of the shaft is extended in order to receive suitable driving connections.

Journalized in bearings 14a on the underside of frame 10, near the center thereof, is a transverse shaft 15, that is rigidly secured to the under side 15 of a longitudinally disposed lever 16, and the end of the long arm of this lever extends beneath the shaft 12.

This shaft provides a fulcrum for the lever and it is located so that the entire lever is positioned 20 in a plane above said fulcrum.

Encircling eccentric 13 is a sleeve 17 and depending from the ends thereof are arms 18 that are positioned to the sides of lever 16.

A short horizontally disposed shaft 19 is carried by the lower ends of the arms 18 and said shaft being journaled in a bearing 20 that is formed on lever 16.

Rigidly fixed to the end of the short arm of lever 16, is an inclined plate 21 and removably positioned on the front face thereof, is the movable jaw 22 of the crusher. The face of this movable jaw is preferably corrugated and projecting rearwardly from the lower portion of jaw plate 22, through openings 23 in the lower portion of plate 21, are lugs 24.

The upper edges of these lugs and the upper edges of the openings 23 are correspondingly inclined so as to cause plate 23 to move upwardly as it moves rearwardly toward plate 21.

Passing through an opening 25 in the upper portion of plate 23, is a bolt 26 that passes through an opening 27 in plate 21 and the upper edge of the head portion of this bolt and the upper portion of opening 25 are correspondingly inclined so as to move plate 22 upwardly when the nut on said bolt is tightened. Brace plate 28 is arranged between the upper portion of fixed plate 21 and the body of lever 16.

The relative stationary jaw of the crusher is arranged between the jaw comprising plates 21 and 22 and said stationary jaw comprises a plate 29 and projecting outwardly from the upper portion of said plate are trunnions 30 that are jour-

naled in bearings 31 on frame 10. This plate 29 is inclined oppositely with respect to plate 21 so that the space between said plates narrows toward their lower ends and mounted on the inner 5 face of plate 29, is a plate 32, the face of which may be corrugated if desired. Plates 22 and 32 are formed of relatively hard wear resisting metal.

Projecting from the upper portion of plate 32 10 are hook-shaped lugs 33 that engage over the upper end of plate 29 and the contacting faces on these lugs and plate 29 are correspondingly inclined so as to tend to draw plate 32 toward plate 29 as said plate 32 is moved downward.

15 Passing through an aperture 34 that is formed in the lower portion of plate 32 and through the aperture 35 in plate 29, is a bolt 36 and the lower edge of the head portion of this bolt and the lower edge of opening 34 are correspondingly inclined 20 so as to tend to draw plate 32 downward when the nut on said bolt is tightened.

Projecting rearwardly from the lower portion of plate 29 adjacent to its side edges, are hooks 37, to which are connected retractile springs 38 25 and the opposite ends of these springs are connected to eye bolts 39 that pass through brackets 40 that depend from the adjacent end of frame 10. These springs tend to pull the lower end of the fixed jaw toward the adjacent end of the 30 frame and the nuts 41 on the bolts 39 may be adjusted so as to vary the tension of springs 38.

Projecting from the end of frame 10 to the rear of the fixed jaw comprising plates 29 and 32, is a bracket 42, through which passes a vertically disposed bolt 43 and mounted on the threaded lower end of said bolt is a nut 44, from the sides of which project short pins 45. These pins provide a support for a plate 46, that is connected to a second plate 47 by bolts 48 and the forward edge 40 of plate 47 occupies a groove 49 that is formed on the rear face of the lower portion of plate 29.

The plates 46 and 47 provide a strut between the lower portion of the stationary jaw and the adjacent end of the frame of the machine and the bolts 48 that connect said plates, provide a 45 factor of safety in that said bolts will shear in the event that a metal tool or other uncrushable object enters the crushing pocket between the jaws and this shearing of said bolts prevents breakage and injury to the crushing jaws or other parts of the machine.

The rear edge of plate 46 bears against lugs 50 that are formed on the adjacent face of the end wall of frame 10, the faces of which lugs are inclined so that as the rear edge of plate 46 is drawn upwardly by manipulation of screw 43, the lower portions of the jaw comprising the plates 29 and 32, will be moved toward the lower portion of the movable jaw and thereby contract the space between the lower portions of the two jaws.

Suitably secured to the side walls of frame 10 at the sides of the crushing jaws 22 and 32, are face plates 51, the adjacent inner edges of which are beveled and removably positioned between 65 said inclined beveled edges, are cheek plates 52 that are positioned to the sides of the crushing pocket or spaced between the jaws. These cheek plates are made removable in order that when they become worn or unfit for service they may be readily removed and replaced by new plates.

Projecting outwardly from the upper portions of the outer faces of the cheek plates, are lugs 53, which facilitate the removal of said plates.

In the operation of my improved lever jaw 75 crusher, shaft 12 is rotated and through eccentric

13 and depending arms 18, the lever 16 is swung upon its fulcrum 15.

In practice I prefer to make the long arm of lever 16 at least twice the length of the short arm thereof, thereby obtaining a two to one leverage 5 of the power imparted to the movable crushing jaw comprising the members 21 and 22.

As the lever is swung upon its fulcrum the movable crushing jaw is simultaneously moved toward and downwardly relative to the fixed jaw and 10 such action is highly effective in producing the desired results.

The material to be crushed is fed into the substantially V-shaped space between the movable and fixed crushing jaws and the action of the 15 movable jaw very rapidly crushes the material delivered into the crushing chamber until such material is reduced to such a size as to permit it to discharge between the lower ends of the crushing jaws.

The relatively stationary jaw may be conveniently adjusted toward or away from the movable jaw by proper manipulation of bolt 43 and should the plates 22 and 32 become worn or unfit for service they may be readily removed from the 25 plates 21 and 29 and replaced by new plates.

Among the important features of my invention are the mounting of the movable jaw of the crusher directly upon the short end of the lever with the fulcrum for the lever located in a plane 30 below that occupied by said lever, together with the relative lengths of the long and short arms of said lever, for by such arrangements the movable jaw during its crushing action moves simultaneously toward and downward relative to the 35 fixed jaw so as to exert great crushing stresses upon the material that is fed into the crushing space between the jaws.

Thus it will be seen that I have provided a lever jaw crusher that is relatively simple in construction, inexpensive of manufacture and very effective in performing the functions for which it is intended.

It will be understood that minor changes in the size, form and construction of the various parts 45 of my improved lever jaw crusher may be made and substituted for those herein shown and described without departing from the spirit of my invention, the scope of which is set forth in the appended claims.

I claim as my invention:

1. In a lever jaw crusher, a fulcrumed lever, a jaw carried by the end of the short arm of said lever, a fixed jaw positioned in front of said lever carried jaw, a pair of plates for supporting the 55 lower portion of the fixed jaw, a sheer pin connecting said plates and means for adjusting said fixed jaw toward or away from said lever carried jaw.

2. In a lever jaw crusher, a lever having its fulcrum located wholly below the body of the lever, means for swinging said lever on its fulcrum, a crushing jaw rigidly mounted on the forward end of the short arm of said lever, a stationary jaw arranged in front of the jaw carried by the lever, 65 a pair of plates arranged between the lower portion of said stationary jaw and a fixed part of the crusher, a sheer pin connecting said plates, an inclined bearing on the frame of the crusher for the outer end of one of said plates and means 70 for raising the end of the plate that engages said inclined bearing.

3. In a lever jaw crusher, a frame, a lever fulcrumed in said frame, the fulcrum of said lever being located wholly below the body of the lever, 75

a crushing jaw rigidly mounted on the forward end of the short arm of said lever, means for swinging said lever on its fulcrum, a jaw pivotally mounted in the frame in front of the lever carried jaw, a retractile spring arranged between the lower portion of the swinging jaw and the frame of the crusher, a pair of plates arranged between

the lower portion of the swinging jaw and the end of the frame, a shear pin connecting said plates, an inclined bearing on the frame for the end of one of said plates and means for raising said plates with respect to said inclined bearing. 5

CHARLES J. ZILLGITT.
